Primary Examiner — Mimosa De(74) *Attorney, Agent, or Firm* — Merchant & Gould PC**CLAIM**

The ornamental design for a chair, as shown and described.

DESCRIPTION

FIG. 1 is a front perspective view of a first embodiment of a chair showing my new design;

FIG. 2 is a rear perspective view thereof;

FIG. 3 is a front elevational view thereof;

FIG. 4 is a rear elevational view thereof;

FIG. 5 is a right side elevational view thereof, a left side elevational view being a mirror image thereof;

FIG. 6 is a top plan view thereof;

FIG. 7 is a front perspective view of a second embodiment of a chair showing my new design;

FIG. 8 is a rear perspective view thereof;

FIG. 9 is a front elevational view thereof;

FIG. 10 is a rear elevational view thereof;

FIG. 11 is a right side elevational view thereof, a left side elevational view being a mirror image thereof; and,

FIG. 12 is a top plan view thereof.

The bottom of the chair is disclaimed. The portions shown in broken lines form no part of the claimed design.
